SUN STALL

Russell Roberts, Fair Haven, Vt.

Application August 6, 1935, Serial No. 34,965

2 Claims. (Cl. 128—372)

This invention relates to sun stalls, and has for the primary object the provision of a device of this character which provides a portable and collapsible wind break for shielding a person while taking a sun bath and may be constructed for either shielding a person while in a reclining position or provide a comfortable seat for a person in a sitting position and which may be readily set up for use and adjusted in position in accordance with the direction in which the wind may blow from and when folded will be compact and convenient to handle and store.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a perspective view illustrating a sun stall constructed in accordance with my invention.

Figure 2 is an edge view showing the device in a folded or collapsed position.

Figure 3 is a transverse sectional view showing the seat arranged within the walls of the stall.

Figure 4 is a fragmentary disrupted perspective view showing the connection between the seat and a member of a wall of the stall and the connection of the back to the seat.

Figure 5 is a detail sectional view taken on the line 5—5 of Figure 1.

Figure 6 is a fragmentary sectional view taken on the line 6—6 of Figure 1.

Figure 7 is a perspective view illustrating a modified form of my invention adapted to shield a person while in a reclining position.

Figure 8 is a fragmentary top plan view illustrating the same.

Figure 9 is an edge view showing the device folded.

Figure 10 is a detail sectional view taken on the line 10—10 of Figure 7.

Referring in detail to the drawings, the numeral 1 indicates a stall designed for shielding a person or acting as a wind break and provides a comfortable seat for a person while in a sitting position. The stall 1 includes side walls 2 and an end wall 3. The end wall is secured to one of the side walls by hinges 4 and to the other side wall by hinges 5. The hinges 4 and 5 permit folding of the device as shown in Figure 2, that is, the end wall 3 may be swung to contact one of the side walls while the other side wall may be folded upon the end wall.

Each side wall is composed of a frame 6

strengthened by a strip 7 forming a rest for a seat 8. The strips 7 are notched, as shown at 9, and the ends of the seat 8 have cleats 10 to engage the strips 7 when said seat 8 rests in the notches 9. Brackets 11 are secured to the rear edge of the seat to removably receive extensions 12 on a back rest 13. The upper end of the back rest carries an extension 14 to fit in a notch 15 formed in the upper rail of the end wall 3. The latter-named wall is similarly constructed to the side walls, that is, composed of a frame. The frames of the walls have a suitable covering applied thereto.

Brackets 16 are provided for attaching the device to the floor. The brackets 16 are secured to the floor by fasteners and carry thumb screws adapted to be turned in engagement with the upper edges of the lower rails of the frames 6. This form of securing means may be substituted by employing on the side members eye bolts 17 in which are slidably mounted spikes 18. The spikes may be positioned in the ground and thereby effectively retain the shield in an operative position.

Referring to my modified form of invention when desiring to construct the device to shield a person in the reclining position the side walls are of a greater length and each includes sections 18 connected by hinges 19. The end wall also is constructed of sections 20 connected by hinges 21. The walls being of sections as described permits the device to be folded into a compact article, as shown in Figure 9. In this form of my invention the seat is omitted.

Employing the device to shield a person either while sitting or reclining, it is preferable that the end wall be disposed in the direction from which the wind is blowing and the person then may have full benefit of sun rays without being subjected to breeze or wind.

A sunshade 18' may be removably mounted to the upper edges of the side walls of the device and capable of adjustment along said side walls for the purpose of protecting the bather's eyes from direct sunlight.

Having described the invention, I claim:

1. A sun stall comprising opposed side walls and an end wall, hinges connecting said walls, a seat member removably secured to the side walls, and a back rest removably secured to the seat member and to the upper edge of the end wall.

2. A sun stall comprising opposed side walls and an end wall each including a pair of sections, hinges connecting the side and end walls, hinges connecting the sections of said walls, and anchoring means for said walls.

RUSSELL ROBERTS.
